UNITED STATES PATENT OFFICE.

WALDO G. MORSE, OF YONKERS, NEW YORK.

DESIGN FOR A SOUND-BOX CASING.

58,615.

Specification for Design.

Patented Aug. 2, 1921.

Application filed May 5, 1919. Serial No. 295,000. Term of patent 7 years.

To all whom it may concern:

Be it known that I, WALDO G. MORSE, a citizen of the United States, residing in the city of Yonkers, county of Westchester, and State of New York, have invented a new, original, and ornamental Design for a Sound-Box Casing, of which the following is a specification, reference being had to the accompanying drawings, forming a part thereof.

Figure 1 is a side view of a sound-box casing showing my new design;

Fig. 2 is a front view thereof; and
Fig. 3 is a rear view thereof.

I claim:

The ornamental design for a sound-box casing, substantially as shown.

This specification signed and witnessed this 21st day of April, 1919.

WALDO G. MORSE.
